DISPLAY CABINET FOR SILVERWARE, ETC.

Thomas J. Pilliod and Ferdinand C. H. Müller,
Swanton, Ohio, assignors to The Pilliod Cabinet
Company, Swanton, Ohio, a corporation of Ohio

Application July 28, 1938, Serial No. 221,774

6 Claims. (Cl. 206—75)

This invention relates to cabinets or chests primarily for containing and for the display of silverware.

The primary object of the invention is the provision of a novel article of this class having a top compartment forming a chest proper and a bottom compartment, such bottom compartment being formed by a removable bottom member in cooperation with the top compartment-forming member and being removable therefrom and adapted to be used for the display of articles or as a serving tray.

Other objects and advantages of the invention will be apparent from the following detailed description and from the accompanying drawings, in which—

Figure 1 is a top perspective view of a cabinet embodying the invention, with a part broken away; Fig. 2 is a perspective view of the tray member of the cabinet removed therefrom; Fig. 3 is a section on the line 3—3 in Fig. 1; Fig. 4 is an end elevation of one corner portion of a cabinet body with the tray member removed, and Figs. 5, 6, 7 and 8 are views of a different embodiment of the invention similar respectively to Figs. 1, 2, 3 and 4.

Referring to Figs. 1 to 4 of the drawings, 1 designates the body section of the cabinet and forms the upper display compartment 2 that is closed by a hinged top 3 in a manner common to cabinets or chests employed for the storing and display of silverware.

This body section includes the lining member 4 formed of suitable stiff material, such as cardboard, covered with cotton flannel or the like and inserted into the body. The front and back sides 1a and the ends 1b of the body section extend below the bottom of the lining member 4 to form the body with a bottom recess.

The bottom section 6 of the cabinet is of tray-like form having a bottom part 6a and opposing sides 6b mounted thereon adjacent to but spaced slightly inward from its side edges, as best shown in Fig. 2. The bottom part 6a is of a size for the bottom edges of the body section 1 to seat down thereon, while the side parts 6b lap the inner sides of the body sides 1a and extend at their ends beyond the body ends 1b through notches 8 in the lower edges thereof. The parts 6b likewise extend at their ends beyond the bottom part 6a of the tray, and adjacent ends of these parts are connected by a hand bar 6c disposed parallel and in slightly spaced relation to the respective body end.

The lining member 4 is provided interiorly

thereof, within the compartment 2, with an article-holding crosspiece 9, as well understood in the art, and the tray member 6 is provided with one or more similar crosspieces 10. The crosspieces 10 are preferably mounted on a strip of stiff sheet material 11 adapted to removably seat down in the tray member 6, so that the parts 10 and 11 may be removed as a unit from the tray when it is desired to use the tray for serving purposes.

It is apparent that to lift the display cabinet as a whole, the handle bars 6c are grasped and raised. Also that to remove the body 1 from the tray member, it is only necessary to raise one from the other.

In the embodiment of the invention shown in Figs. 5 to 8, the body section is designated 15 and the bottom or tray section 16. The body 15 is of the same general construction as the body 1 of the previous form, except that its ends 15b terminate at their lower edges substantially flush with the bottom of the lining member 17' of the body. The lower edge portions of the front and back sides 15a of the body 15 project downward below the plane of the lining bottom 17' and rest upon the side edge portions of the tray bottom.

In this form, the tray 16 comprises the bottom part 16a, the upstanding side parts 16b disposed at the opposite ends of the bottom member 16a, and the bars or rod-like members 16c, which are inwardly spaced from the front and rear side edges of the tray bottom 16a and connect the respective ends of the sides 16b. The side parts 16b are of a shape and size to fill the space provided at the bottom end edges of the body ends 15b by the terminating of such ends substantially flush with the bottom of the lining member 17'. When the body 15 and tray 16 are assembled, the front and rear sides 15a of the body rest on the respective edge portions of the tray bottom part 16a and the shallow end portions 15b of the body rest on the upper ends of the tray side parts 16b, so that the sides and ends of the body and the side part 16b of the tray cooperate to form, in appearance, a closed body wall with the bottom part 16a of the tray serving as the bottom member of the body. To facilitate lifting the cabinet in this assembled form, the side parts 16b of the tray are provided at their outer sides with handle parts 17.

It is apparent that in each form of the invention the cabinet may be used to form an upper and lower compartment for containing silverware or the like and, for display purposes, the body and tray sections may be separated and

placed so as to display the silverware or other articles contained in either or both. It is also apparent that in either case the tray section may be used as a serving tray by simply removing the article-holding portion therefrom. Also that in either case the body section has a depending skirt portion for resting on the bottom section, which skirt portion is recessed to receive upwardly projecting portions of the bottom section to which exposed handles are attached. In the case of the form shown in Figs. 1 to 3, this article-holding portion comprises the parts 10 and 11 and, in the form shown in Figs. 5 to 7, such portion comprises the removable sheet part 18 on which the rack part 19 for engaging the articles is mounted.

We wish it understood that our invention is not limited to any specific construction, arrangement or form of the parts, as it is capable of numerous modifications and changes without departing from the spirit of the claims.

Having thus described our invention, what we claim as new, and desire to secure by United States Letters Patent is:

1. An article of the class described comprising a body section and a bottom section, the body section forming a top display compartment and having its sides and ends projecting below the bottom of said compartment to form the body section with a bottom recess, opposing sides of said body section having their lower edges notched, said bottom section including a bottom member on which the sides of the body section seat and having side members projecting upwardly within said bottom recess with their ends projecting outwardly through respective of said notches, and hand bars connecting said projected ends without the respective sides of the body section, said bottom section cooperating with the body section, when assembled therewith, to form a bottom compartment and, when removed therefrom, adapted to be used as a display tray or as a serving tray.

2. An article of the class described comprising a body section and a bottom section, the body section having a bottom, sides and ends forming a top display compartment and having the bottom edges of its sides extended below said compartment bottom to form the body section with a bottom recess, said body section having its ends provided with cut away parts, and said bottom section including a bottom part on which the sides of the body section seat and also having upstanding end members which fit into the cutaway parts of the body section ends so as to close said cutaway parts when the two sections are in assembled relation, bars connecting the respective end portions of said upstanding members and disposed within the bottom recess

of the body section when the two sections are in assembled relation, and handles attached to the outer sides of said upstanding members, said bottom section, when removed from the body section, being usable as a display tray or a serving tray.

3. An article of the class described comprising a body section forming a top display compartment and having side walls and a bottom set inwardly relative to the lower edges of said side walls to form a supporting skirt portion, said skirt portion having a plurality of inwardly extending recesses in its lower edges, and a bottom section of tray-form on which said skirt portion rests and having handle carrying parts which project up into said skirt recesses when the bottom section is mounted thereon and providing exposed handles at the respective outer sides of the body section, said bottom section cooperating with the body section when assembled therewith to form a closed article containing compartment and adapted when separated from the body section to form an article display section and a serving tray.

4. An article of the type set forth including an upper and a lower member, the upper member having a top and side and end walls, a bottom carried by the upper member and disposed spaced above the lower edges of the side and end walls, the lower member having a bottom, handle elements at its ends and side elements connecting the handle elements and spaced inwardly of the side edges of the bottom of the lower member, said connecting elements extending upwardly from the bottom of the lower member to form sides therefor, the side walls of the upper member being receivable over said connecting elements of the lower member and seating on the bottom of the lower member and being engageable with said connecting elements to hold the upper member against transverse sliding on the lower member, the end walls of the upper member being located inwardly of the handles proper whereby the latter project outwardly beyond the end walls of the upper member when the latter is seated on the lower member.

5. An article in accordance with claim 4, wherein the handle elements include members forming end walls for the lower member and wherein the bottom edges of the end walls of the upper member seat on the top edges of said end walls of the lower member.

6. An article in accordance with claim 4, wherein the end walls of the upper member are recessed to receive therethrough the outer ends of the connecting elements of the lower member.
